UNITED STATES PATENT OFFICE.

JOSEPH W. MYERS, OF JACKSON, MICHIGAN, ASSIGNOR, BY DIRECT AND MESNE ASSIGNMENTS, OF ONE-THIRD TO JOSEPH H. MYERS, OF JACKSON, MICHIGAN; ONE-THIRD TO ARTHUR J. TUTTLE, OF DETROIT, MICHIGAN; AND ONE-THIRD TO AGNES W. MYERS AND JOSEPH W. MYERS, BOTH OF JACKSON, MICHIGAN.

FLATIRON.

Application filed March 24, 1924. Serial No. 701,404.

My invention relates to flatirons and an object of my improvements is to provide an electrically heated flatiron, the temperature of which shall be automatically and effectively regulated. I also provide an apparatus that is easily adjusted to different types of irons, that secures a sharp make-and-break of the electric circuit, and one in which the thermostatic agent is free from strain when not in use, and which provides a simple and accessible means for adjusting the temperature. In the accompanying drawings:—

Figure 1 is a side view of an apparatus embodying my invention partly broken away to show the interior construction.

Fig. 2 is a plan view of the same, the cover being removed.

Fig. 3 is a detailed elevation partly in section showing a modified construction of the temperature adjusting apparatus.

Referring to Figs. 1 and 2, *a* is the bottom plate, *b* is the top plate, and *c* the flat heating element held between the plates *a* and *b*.

This is a usual and conventional construction.

*a*² is a slot cut in from the upper surface of the bottom plate. *b*² is a cylindrical aperture extending vertically thru the plate *b* and opening to the slot *a*². *d* is a bimetallic strip constituting a thermostatic element secured at *d*² in the slot *a*² at the end near the edge of the bottom plate and extending along the lower wall of said slot to a point in this instance somewhat beyond the center of the iron.

e is the base plate of the make-and-break apparatus for the electric current. The base plate *e* is secured to the upper surface of the plate *b* with an aperture therethrough registering with the aperture *b*². There is also an aperture *e*⁴ through this base plate registering with a vertical aperture *b*³ through the plate *b* communicating with the slot *a*². *e*² is a contact point at one edge of the base plate *e*.

f is a flexible strip secured to the base plate *e* at *f*², a point remote from that at which the contact point, *e*², is located. The strip *f* extends across the base plate *e* to a point at which an adjustable contact point, *f*³, is located, just above the contact point, *e*². *f*⁴ is a piece of sheet metal clamped to the

free end of the strip, *f*, at the contact point, *f*³, bending downward and then inward at 55 its inner end so as to form a socket for the purpose hereinafter described. *e*³ is a similar strip of metal secured to the base plate *e* at *e*², extending inward then bending upward and outward to form a socket opposed 60 to the socket in the strip, *f*⁴. In this case the sockets in the strips *f*⁴ and *e*³ are in a horizontal plane. *k* is a U-shaped spring. The two branches of the spring *k* are bent toward each other and engaged in the loops 65 of the strips *f*⁴ and *e*³, so as to exercise forces against said loops because of the elasticity of the spring. The relative position of said loop is such that when the points *f*³ and *e*² are in contact the outer branch of the spring 70 is a trifle below the inner branch so that the spring pressure has a resultant effect to force the contact points together. When the loop in the piece *f*⁴ is slightly raised it will pass by the dead center and then the elasticity 75 of the spring *k* will act to force the contact points *f*³ and *e*² apart.

m is a screw threaded rod adjustably secured at its upper end to the strip *f* and extending downward through the aperture *b*² 80 to a point slightly above the free end of the thermostatic strip *d*. The distance of the lower end of the rod *m* above the thermostatic strip *d* may be adjusted by means of the nuts connecting said rod to the strip *f*. 85

g is a small rod passing through the aperture, *b*³, in the top plate *b* and resting at its lower end upon the upper surface of the thermostatic strip *d*.

j is the cover secured to the base plate *a* 90 and enclosing the heating elements *c*, the upper plate *b*, and the make-and-break apparatus. *h*⁴ is a cylindrical rod extending vertically through the upper wall of the coverplate *j*, and provided at its upper end 95 with means adapted to be manipulated to turn the rod *h*⁴ about its axis. *h*³ is a pointer connected with the rod *h*⁴ and serving to indicate the angular position of said rod.

h is a flat spiral spring secured at its center to the lower end of the rod *h*⁴ and bearing upon the upper end of said rod. By turning the rod *h*⁴, the spring *h* exercises more or less pressure upon the upper end of the rod *g*, which is communicated through 100 said rod to the thermostatic strip *d*.

In Fig. 3, an alternative form of the adjusting mechanism is shown. In this the spiral spring h is replaced by a rigid cam ha , and the rod g is replaced by an elastic rod, ga^2 .

It will be observed that the actuating thermostatic strip d travels some distance before it commences to act upon the elastic strip f and that such action is at a point adjacent to the attachment point f^2 of the strip f and remote from the contact points f^3, e^2 , so that any motion imparted to said strip will be multiplied when transmitted to the contact point f^3 .

In an iron of this kind, the cloth being operated upon is frequently moistened and the heat is withdrawn more rapidly from the lower plate which is the operating part of the iron and therefore from the part, the temperature of which it is desired to regulate. I therefore put the thermostatic element directly in contact with the operative plate which, in the first form of the construction, employs the upper and lower plates.

In this construction the heating elements engaged between the two plates are of such form and extent that they do not come over the opening a^2 and therefore they cannot radiate directly to the thermostatic element.

The operation of the above described device is as follows:—

First referring to the form shown in Figs. 1 and 2, when the temperature of the plate a rises the heat is communicated to the thermostatic strip d which begins to bend upward until it comes in contact with the lower end of the rod m , as shown in broken lines in Fig. 1. Its force is then exerted upon said rod and therethrough upon the strip f , which is pressed upward carrying the spring h beyond its dead point and developing the elasticity of said strip. When the force has become sufficient the contact between the points f^3 and e^2 is broken and the point f^3 is carried quickly upward and away from the point e^2 by the developed elasticity of the strip f and by the snapover action of the spring k .

The temperature at which the thermostatic element shall act may be adjusted by rotating the rod h^4 , and therefore putting more or less pressure upon the upper surface of the thermostatic element to resist the action thereof, or the position of the rod m may be adjusted so that its lower end is nearer to, or further away from the strip d .

In the modification of the regulating apparatus shown in Fig. 3, instead of the elastic spiral spring h , the elastic element is incorporated with the rod g , as shown at ga^2 , Fig. 3.

It will be noticed that the above described apparatus is easily adjusted to either form of the iron shown and commonly used.

The point of contact of the thermostat with the strip f at a distance from its movable end and the snapover spring k , secure a quick make-and-break action.

It will be noticed that the thermostatic strip travels some distance before it exercises its actuating force, and that the means for adjusting the temperature is accessible, simple, and convenient.

The lower surface of the iron is the operative part and the heat is taken from this surface in use and at a varying rate. I therefore place the thermostatic element in close connection with the material that this surface bounds, and convey the mechanical action of the thermostat to apparatus located at a convenient and accessible point where it is not liable to be injured in the use of the iron.

What I claim is:—

1. In an electrically heated flatiron a removable cover therefor a circuit controlling apparatus, a thermostat adapted to actuate said apparatus, and a cam forming an adjustable yielding force modifying the action of said thermostat, said cam being itself elastic, said cam being permanently secured to said cover and adapted to automatically engage to actuate said apparatus when the cover is adjusted to the iron.

2. In an electrically heated flatiron, a removable cover therefor a circuit controlling apparatus, a thermostat adapted to actuate said apparatus, and a spiral spring cam rotatable in a horizontal plane and forming an adjustable yielding force modifying the action of said thermostat, said cam being adapted to engage said apparatus by a vertical movement as the cover is placed in position.

3. In an electrically heated flatiron having an upper and lower plate with an intermediate heating element, a thermostat in direct heat-receiving relation to the lower of said plates and located below the upper plate, a circuit controlling apparatus biased to keep the circuit closed and located above said thermostat upon said iron, and means whereby the motion of said thermostat shall actuate said controlling means to open and close said circuit.

4. In an electric flatiron having an upper and lower plate with an intermediate heating element, a thermostat related to the lower plate and located below the upper plate, a circuit controlling apparatus biased to keep the circuit closed and located above said thermostat upon said iron and mechanical means whereby the motion of said thermostat shall actuate said controlling means to open and close the circuit.

5. In an electrically heated flatiron having an upper and lower plate with a heating element therebetween, a thermostat related to said lower plate and located below the

upper plate, a circuit controlling apparatus having a movable arm above said plates, said iron being provided with an aperture through said upper plate and element, and a 5 rod upon said arm extending into said aperture to a point adapted to be engaged by said thermostat, said thermostat being relatively so located that it shall move a distance before engaging said rod and means 10 for adjusting the position of said rod to secure an earlier or later engagement of said thermostat.

6. In an electrically heated flatiron having an upper and lower plate with an interposed 15 heating element, said iron being provided with a vertical aperture through said upper plate and element, a thermostat related to said lower plate in such a manner as to receive heat freely therefrom and located be- 20 low the upper plate, a rod passing through said aperture and engaging upon said thermostat and said means above said upper plate for acting upon said rod, to regulate the action of said thermostat.

25 7. In an electrically heated flatiron having an upper and lower plate with an interposed heating element, said iron being provided with a vertical aperture through said upper plate and element, a thermostat related 30 to said lower plate in such a manner as to receive heat freely therefrom and located below the upper plate, a rod passing through said aperture and engaging upon said thermostat and means above said upper plate for acting 35 upon said rod, to regulate the action of said thermostat, and an elastic member in said regulating means.

8. In an electrically heated flatiron having an upper and lower plate with an interposed heating element, said iron being provided with a vertical aperture through said upper plate and element, a thermostat related to said lower plate in such a manner as to receive heat freely therefrom and located below the upper plate, a rod passing 40 through said aperture and engaging upon said thermostat and means above said upper plate for acting upon said rod, to regulate the action of said thermostat, means for applying a yielding variable force to the 45 upper end of said rod.

9. In an electrically heated flatiron, the combination of an upper and lower plate, a thermostat located below said upper plate, a circuit controlling apparatus above said 50 thermostat, a groove in the upper surface of the lower plate, means for communicating the motion of the thermostat to said apparatus, the heating element between said plates being so formed and located that it 55 shall not communicate heat directly into said groove.

10. In an electrically heated flatiron, a base plate, an arm carrying a contact secured to said base plate, said arm biased to 60 keep the circuit of said iron closed, a thermostatic strip arranged to actuate said arm to open the circuit, variable resilient means for acting on said thermostat to alter the temperature of actuation of said arm by 65 said thermostat.

In testimony whereof, I sign this specification.

JOSEPH W. MYERS.
